MERCHANDISING DISPLAY STAND FOR WRITING INSTRUMENTS AND THE LIKE

Thaddeus I. Kingsford, 3215 Embry Circle, Chamblee, Ga., and Frank Van Haltern, Jr., 1857 Ferncreek Lane NE., Atlanta, Ga.

Filed Mar. 5, 1965, Ser. No. 84,098

Term of patent 14 years

(Cl. D80—9)

FIG. 1

FIG. 3

FIG. 2

FIG. 4

6

FIG. 6

FIG. 5

FIG. 4

FIG. 1 is a perspective view of the merchandising display stand for writing instruments and the like embodying our new design;

FIG. 2 is a front elevational view of the merchandising display stand shown in FIG. 1;

FIG. 3 is a side elevational view thereof having its upper hingeable panels that are adapted for holding writing instruments disposed in the upright position;

FIG. 4 is a rear elevational view thereof showing its upper hingeable panels in the upright position and its lower hingeable panels in a forwardly inclined position;

FIG. 5 is a top plan view thereof; and

FIG. 6 is a longitudinal cross sectional view taken along the line 6—6 of FIG. 4.

The dominant features of our design reside in the portions illustrated in full lines.

We claim:

The ornamental design for a merchandising display stand for writing instruments and the like, as shown and described.
